UNITED STATES PATENT OFFICE

GEORGE DENECKE, OF MILWAUKEE, WISCONSIN

LIGHT SUPPORT

Application filed June 5, 1929. Serial No. 368,583.

This invention relates to new and useful improvements in light supports.

One of the objects of my invention is the provision of a light support which can be quickly and readily attached to a stationary support and is so constructed and arranged as to readily support the light in various adjusted positions and the light bulb and shade is loosely mounted so that in case the main support is attached to an object receiving chattering or jarring movement, there will be no jarring or shaking of the light itself.

Another object of the invention is the provision of an adjustable light support which is particularly adapted for use on sewing machines and especially machines which are used by tailors and garment makers, so that the lamp can be adjusted to move the same toward or away from the work being operated upon, and the support is so constructed as to prevent any shaking or jarring movement of the machine during its operation from being conveyed to the light bulb.

Another object of the invention is the provision of an adjustable light support which comprises a base carrying a clamping member adapted to engage over the edge of a table or stand and rising from the base is a standard having a lateral supporting arm pivotally connected to its upper end with a brace member pivotally connected to the supporting arm and adjustably engaged with the standard whereby the lamp is loosely supported at the outer end of the arm and can be raised and lowered to different heights according to the machine to which the device is applied.

With the above and other objects in view, the invention consists in the novel features of construction, the combination and arrangement of parts hereinafter more fully set forth, pointed out in the claim and shown in the accompanying drawing wherein:

The accompanying drawing illustrates in elevation the application of my improved adjustable lamp support with parts thereof broken away and illustrated in cross section.

In the accompanying drawing, I have illustrated my improved lamp attached to a support 1. This support may be the edge of a

supporting table of a sewing machine or any other type of support.

The lamp proper comprises a base member 2 to the lower side of which is attached one arm of a substantially U-shaped spring clamp 3. The other arm of the spring clamp is slightly inclined or bowed so that it will yieldably bear against the underside of the support 1 for holding the base member 2 in position on the support. Rising from the base is a standard 4, the lower end of which is formed with a cylinder reduced part 5, attached to be fitted into a central opening in the base 2.

The upper end of the standard is bifurcated to form spaced ears 6, receiving there between the inner end of the adjustable arm 7. The pin 8 is extended through the ears 6 and through the inner end of the arm 7 for pivotally mounting the arm to the upper end of the standard.

The outer end of the arm 7 is formed with a perforation 9 adapted to receive therethrough one end of an S-shaped hook 10. The other end of the hook supporting the lamp 11 which is at its upper end, a loop 12 adapted to engage one end of the hook 10. The lamp 11 may be of any well known type and is connected by means of a conductor 13 which is slidably mounted within the guide bands 14 carried by the arm 7.

It will be apparent from this structure that the lamp 11 may be disengaged from the hook 10 and the cord extended by pulling the same through the guides 14. In passing the cord backwardly from the lamp 11, it is preferred to extend the same between the ears 6 so as to prevent the same from dropping down in any manner between the standard and the lamp.

The standard 4 is provided upon one side thereof with a diagonal cutaway portion 15 which adjustably receives the lower end of a diagonal brace member 16, the upper end of the brace member being pivotally connected to the arm 7 between its ends as shown at 17. The lower end of the arm 16 is provided with a plurality of apertures 18 and in order to adjustably connect the arm 16 to the standard 4, a removable pivot

pin 19 is provided which is adapted to be extended through any one of the openings 18 and engage with the standard. It may be found desirable, however, to have the pin 19 carried by the standard 4 and the arm 16 5 detachably engaged therewith.

It will be apparent from the foregoing that in using my improved light support in connection with a sewing machine, the standard 4 can be engaged with the table of the machine on the side thereof opposite the operator, and the lamp 11 suspended directly above the work being performed and the arm 7 may be raised or lowered in order 10 to bring the lamp 11 in proper position for clearly illuminating the work.

While I have specifically set forth the fact that the device is particularly adapted for use in connection with sewing machines 20 and the like, it can be used equally as well in various other places.

While I have shown and described the preferred embodiment of my invention, it will be apparent that slight changes may be made 25 in the construction when putting the invention into practice without departing from the spirit of the same or the scope of the appended claim. Also in some instances it may be desired to eliminate the use of the attaching clamp, in which case it is merely necessary to provide an opening in the sewing machine or support for reception of the shank 5.

I claim—

30 A light support including an upright standard having a diagonal cut away portion adjacent its upper end, spaced ears at the upper end of the standard, an arm having one end pivotally mounted between the ears and adapted to project laterally from the standard, a brace member having one end pivotally connected to the arm and the other end movable through the diagonal cutout portion and provided with a plurality 35 of spaced openings, a removable pivot pin carried by the standard and adapted to be positioned in any one of said openings for maintaining the arm in various positions relative to the standard, spaced guide loops carried by the arm and a light suspended 40 from the outer end of the arm and having a cord projecting therefrom adapted to be passed out through the guide loops and between the spaced ears on the standard for maintaining the cord in position above the light and to prevent the same from dropping down onto the work beneath the light.

45 In testimony that I claim the foregoing I have hereunto set my hand at Milwaukee, in the county of Milwaukee and State of Wisconsin.

GEORGE DENECKE.
